Application June 6, 1938, Serial No. 212,165
In Germany October 10, 1936

9 Claims. (Cl. 271—53)

This invention relates to a printing machine provided with rocking cylinders and automatic sheet feed and delivery, and particularly to improvements in the sheet feeding means.

One object of the invention is to provide a drive for the carriage and impression cylinder so as to permit stopping of the impression cylinder when a sheet is fed or taken over by the grippers of the impression cylinder without interrupting the drive. According to the invention, this end is attained by connecting a crank disc acting as planet wheel with a lever arrangement or a toothed wheel rolling on a rack for reciprocating the carriage, so that at the end position of the carriage utilized for feeding, and adjusting the sheet the rod connecting the lever or the toothed wheel with the crank pin of the planet wheel describes about its link pin on the lever or the shaft of the toothed wheel a circle a segment of which will register with a segment of the curve described by the crank pin of the planet wheel, so that a motion of the carriage and impression cylinder, which could interfere with feeding and adjusting, does not occur.

Another object of the invention is to provide means according to which the sheet carrying and holding devices at the transfer of the sheet to the grippers, which covers a short period before and after the change in the direction of rotation of the cylinder, are coupled with the cylinder and driven by it or are moved by springs so as to follow the cylinder. The purpose of this arrangement is to prevent the cylinder at the sheet transfer from carrying out a special motion relative to the sheet holding device and to avoid interruption of the cylinder drive for the sheet transfer. The sheets are not fed to and adjusted by cylinder marks but are straightened by front gages of the feed table, whereby better and perfectly steady feeding and adjustment are insured. The sheets are then taken over by the cylinder grippers in such manner that at the transfer the sheet carrying and holding means are displaced in harmony with the cylinder motion.

The removal of the sheets from the gages of the feeding table by the cylinder grippers in such manner that the sheet holding means carry out a movement corresponding to the cylinder motion does not necessarily require temporary stopping of the cylinder, but the use of the cylinder drive mentioned above which automatically causes a short standstill of the cylinder when the change in the direction of rotation occurs

insures steady sheet transfer to a still higher degree.

When the sheet is directly taken up from the front gages of the feed table, the latter, preferably of the swing type and provided with a tilting drive, or a portion thereof adjoining the cylinder and fitted with front gages is displaceably guided under spring tension approximately tangentially to the cylinder and is moved back with the cylinder by being for instance carried along by a driver on the cylinder. It is further possible to employ a swinging feed table or a portion thereof, fitted with front gages and possibly with means for securing the adjusted position, to which an oscillating motion corresponding to the partial rotation of the cylinder at the moment of closing of the grippers is imparted by suitable driving means, as a lifting cam disposed on the cylinder.

The displaceably guided feed table or portion thereof is preferably fitted with means, as suction nozzles, for securing the sheet in adjusted position during the transfer.

The invention further provides that the portion of the feed table adjacent the impression cylinders, together with the means arranged thereon, as marks, lateral adjusting means, bar lattice, etc., can be swung about a pivot located between the impression cylinders and the sheet delivery means and that the remaining portion of the feed table can be turned up about a shaft arranged on the feeding frame. This arrangement facilitates the exposure of the impression cylinder for making ready and renders the inking apparatus more accessible. It is possible of course to movably dispose the entire feeding table at the feeder frame.

In case of a gap provided between the feed table and the cylinder and the transfer of the sheets to the cylinder by means of intermediate grippers, etc., the intermediate grippers or suckers which hold the sheet or a portion of the table to which the intermediate grippers or suckers are attached are, according to the invention, positively connected with their drive and are moved in harmony with the motion of the cylinder grippers, for instance, by the action of a driver attached to the cylinder. The intermediate grippers may be swinging elements and receive a corresponding drive through correspondingly formed driving members, as cam plates, etc.

In further accordance with the invention one or more additional inking rollers, possibly provided with distributing rollers, are provided in

addition to the main inking apparatus disposed in known manner below the hinged feed table, which are supplied with ink by a table inking appliance moved to and fro with the carriage, so that in connection with the rotation of the impression cylinder exceeding one revolution owing to the sheet delivery good inking of the form is insured. The additional inking rollers may be arranged on the same side of the cylinder as the main inking apparatus or on the other side.

By way of example, several embodiments of the invention are illustrated in the accompanying drawings, in which

15 Figure 1 is an elevation of the general construction of the machine, in which the cylinder grippers receive the sheet directly from the front gages of the feed table;

20 Fig. 2 shows another form of the carriage drive; Fig. 3 is an elevation on an enlarged scale of the upper part of the machine;

25 Fig. 4 is a plan of a detail shown in Fig. 3;

Figs. 5 and 6 are, respectively, an elevation and a plan on an enlarged scale of another form of feed table; and

30 Figs. 7 to 10 are elevations showing modified details of construction.

In the machine frame 1 the impression cylinder 2 is rotatably disposed. The grippers 3 of the cylinder 2 are supplied with sheets from the feed pile 4 by the conveyors 5 of the feed table 6 which can be moved about the shaft 7 of the tape roller 8. The feed table 6 possesses an extension 9, Fig. 3, displaceably arranged in laterally positioned bearing plates 10 and reaching up to the impression cylinder 2. The bearing plates 10 can be turned by means of the handles 11 about pins 13 located between the impression cylinder 2 and the sheet delivery means comprising an endless band 12, as indicated in Figs. 1 and 3. The extension 9 is displaceably guided in the plane of the table between the bearing plates 10 and for this purpose provided with guides 14 which are movably disposed on the extension 9 by the pins 15 and are displaceably guided in guides 16 on the bearing plates 10. The guide members 14 are subjected in the guides 16 to the pressure of springs 17 which force the table extension 9 against the impression cylinder 2 into an end position. As the extension 9 is movable about the pin 15, its end adjoining the cylinder 2 can be raised to deliver the printed sheets by a lifting linkage 18 controlled by a shaft, which is only slightly indicated. Furthermore, between the bearing plates 10 upwardly movable front gages 20 are provided on a shaft 19 for receiving the sheets conveyed to them from the pile 4 by the tapes 5 of the feed table 6.

The table extension 9 has a projection 21 serving as stop and extending into the path of a driver 22 projecting from the cylinder 2, so that the driver 22 at the return of the cylinder in the direction of the arrow shown in Fig. 3 drives the extension 9 and pushes it back against the pressure of the spring 17. When the direction of rotation is altered, the table extension 9 follows the driver 22 of the cylinder 2 while the spring 17 expands until the member 9 reaches its end position. During the printing operation the cylinder 2 turns in a direction opposite to that indicated by the arrow in Fig. 3.

Before the rotation for effecting printing is completed, the table extension 9 is swung about the pins 15 and slightly lifted by the linkage 18 to deliver the sheets. The printed sheets are

guided from the cylinder 2 over the bridge 23 to the delivery device 12 which places them on the pile 24. When the extension 9 is lifted, its stop 21 is moved out of the path of the driver 22 of the cylinder 2, so that the driver 22 can freely pass. During the return motion of the cylinder 2 the extension 9 together with the sheet contacting with the front gages 20 is lowered into its former position and, when the driver 22 strikes the stop 21, taken along by the cylinder to the end of its return motion, i. e., pushed back upon the guide member 14 against the pressure of the springs 17. After the change in the direction of rotation of the cylinder the table extension 9 follows the driver 22 under tension of the expanding springs 17. During this brief to and fro motion of the extension 9 together with the cylinder 2 the sheet is taken over by the grippers 3 and released by moving the front gages 20. The closing of the grippers can be effected during the rearward or forward motion of the cylinder 2 and of the extension 9.

Below the hinged feed table 6 the inking apparatus is arranged which comprises the ink fountain 24, the ink fountain roller 25, the ductor 26, the distributing rollers 27, 28 and the inking rollers 29, 30, 31 of which the rollers 30, 31 ink the form 32. Besides the inking rollers 30, 31 one or more inking rollers 33, 34 are provided which are not directly supplied with ink from the fountain through the ductor 26 but receive their ink indirectly through the medium of a table inking appliance 35 which moves to and fro with the form 32 and during this motion receives ink from the rollers 30, 31 and transmits it to the rollers 33, 34.

The printing form 32 and the table inking appliance 35 are secured to a carriage 36 reciprocatorily guided below the impression cylinder 2 and driving in known manner, not shown, the impression cylinder 2 which is lifted off from the form during its return motion. The carriage 36 engages with a rack 37 attached to its underside the toothing of a spur gear 38 which meshes with a rack 39 firmly arranged in the machine bed and can roll on the latter rack. The shaft 40 of the gear 38 is engaged by one end of a rod 41 whose other end is articulated to a crank pin 42 of a crank disc 43 which forms the planet wheel of a planet gear and meshes with the stationary toothed wheel 44 about the shaft 45 of which a toothed wheel 46 rotates on which the planet wheel 43 is rotatably disposed by means of the pin 47.

In the construction shown in Fig. 2 the carriage 36 is reciprocated by the connecting rod 41 through a lever drive comprising a lever 49 movable about a shaft 48 and articulated at its free end to a projection 51 of the carriage by means of a link bar 50. Fig. 2 shows the carriage drive at the left dead center position of the planet gear, the other dead center position being indicated by dash-and-dot lines. The curve described by the crank pin 42 of the planet wheel 43 is plotted in Fig. 2 and designated 52. It shows that in one section on both sides of the left dead center position of the crank pin 42, indicated by solid lines, the motion of the lever 49 is so slight that the carriage 36 as well as all parts whose motion depends upon the motion of the carriage, including the impression cylinder 2, stand still.

To this position of the carriage drive corresponds the position of the impression cylinder 2, 71

shown in Fig. 1, at which the cylinder grippers 3 take over the sheet.

As shown in Figs. 5 and 6, the table extension 9 may be articulated to the feed table 6 and swung with the latter about the shaft 7. The extension 9, in the construction shown, is articulated to the table 6 by means of straps 53 secured to the table 6 and by link pins 54 engaging the extension 9 and displaceably guided with their head in a slotlike clearance 55 of the straps 53 against the pressure of springs 56. In this way, the extension 9 is displaceably guided in the plane of the table and can be swung about the pins 54.

In the construction shown in Fig. 7 the displaceably and swingably disposed extension 9 is provided with means for holding the sheet in adjusted position and preventing any displacement thereof. Such means may comprise suction nozzles or pressure fingers, etc. The suction means may be provided on the sheet support or extension 9 or, as shown in Fig. 7, form a suction bar 57 controlled so that its suction members after adjustment of the sheet by the front gages 20 engage the sheets by suction and release each sheet after the closing of the grippers.

In the constructions described the cylinder grippers directly receive the sheet from the gages of the feed table and the gap between the feed table and the cylinder for delivering the sheet is produced by lifting the feed table, but the arrangement may also be such that a space is provided between the feed table and the cylinder and the sheets are conveyed from the table gages to the cylinder grippers by means of intermediate grippers.

In the construction shown in Fig. 8 the sheet guided to the front gages 20 and adjusted by them is passed by a reciprocating suction bar 58 into the position shown in Fig. 8, at which the transfer of the sheet is effected by the grippers 3 of the cylinder 2. The suction bar 58 is arranged on a slide 59 displaceably guided by a member 60 and connected by a rod 61 with the free end of an arm 62 which swings about a pin 63 and is moved to and fro by suitable means, not shown. The rod 61 is longitudinally displaceably guided in a member 64 movably disposed at the free end of the arm 62. Between an adjusting ring 65 and the guide member 64 a spring 66 is provided and restricted in its action by the enlarged head 67 of the rod 61. Fig. 8 shows the position of the parts at the time when after lifting of the front gages 20 the slide 59 of the suction bar 58 with the sheet held by the suction member is advanced into the position at which the sheet is taken over by the cylinder grippers. The slide 59 possesses at its front end a downwardly directed stop or nose 68 which is engaged by the driver 22 of the impression cylinder 2 shortly before the latter completes its return motion. The slide 59 is forced back by the driver 22 against the action of the spring 66 and after the change in the direction of rotation follows the driver 22. During this motion of the slide 59 the cylinder grippers are closed while the suction bar 58 releases the sheet.

In the embodiment shown in Fig. 9 the members which transfer the sheet from the front gages of the feed table to the position at which it is taken over by the cylinder grippers are formed as oscillating grippers. The suction members 69 are disposed on a shaft 70 constructed as suction pipe and supporting an arm 72 which is fitted with a roll 71 and controlled by a cam 73 cooperating in the rotation of the cylinder 2. Another

arm 74 on the shaft 70 is controlled through the medium of a bar 75 by a suitable control member, cam, eccentric, etc., not shown, in such manner that the suction members 69 carry out a swinging motion to convey the sheet from the front gages 20 into the position shown. The arm 74 is yieldably connected with the bar 75 in one direction, since a slide 76 articulated to the arm 74 and guided on the bar 75 is pressed by a spring 77 against a ring 78 secured to the bar 75, so that the cam 73 is enabled to move the suction arms 69 independently of the control bar 75. The cam 73 effects a short to and fro motion of the members 69, which exactly corresponds to the motion of the cylinder 2 at the change in the direction of rotation.

Fig. 10 shows a construction which differs from the one shown in Fig. 7 only in so far as the table extension 9 is not rectilinearly displaceable and not engaged and taken along by a driver of the cylinder 2, but is swingably arranged by means of a lever system 79 of the parallelogram type. The front pair of levers is connected with a roller lever 80 the roller 81 of which moves on a cam 73 rotating with the cylinder 2 and is drawn against the back of the cam by a spring 82 engaging the arm 80. During the portion of the cylinder motion at which the grippers are closed the cam 73 produces a reciprocating motion, corresponding to the cylinder motion, of the table extension 9, in which the front gages 20 and suction members 57 provided for keeping the sheet in adjusted position participate.

I claim:

1. A printing machine of the rocking cylinder type provided with automatic sheet feed and delivery and a cylinder driven by means of a reciprocating carriage, said carriage being provided with a rack and the cylinder being provided with a gear adapted to mesh with said rack, in which the carriage is driven from a crank disc forming the planet wheel of a planet gear by means of a toothed wheel rolling on a rack and engaging a rack of the carriage in such manner that when the sheet is taken over by the grippers of the impression cylinder the cylinder temporarily stops without any interruption of the drive.

2. A printing machine of the rocking cylinder type provided with automatic sheet feed and delivery and a cylinder drive by means of a reciprocating carriage, in which, when a sheet registered by the gages of the feed table is taken over by the cylinder grippers, the grippers, before and after the change in the direction of rotation of the cylinder are moved forward and backward in unison with the table.

3. A printing machine according to claim 1, in which, when a sheet registered by the gages of the feed table is taken over by the cylinder grippers, the grippers, before and after the change in the direction of rotation of the cylinder are moved forward and backward in correspondence with the table.

4. A printing machine according to claim 2, in which a gap is provided between the feed table and the cylinder and the adjusted sheet is delivered to the cylinder by intermediate grippers, suction bars, etc., and in which said grippers cooperate before and after the change in the direction of rotation of the cylinder for a short distance in the motion thereof by being for instance positively connected with their drive and are taken along by a driver of the cylinder before the completion of the return motion.

5. A printing machine according to claim 2, in which, when the sheets are directly taken off from the feed table by the cylinder grippers, the feed table formed in known manner as swinging table and fitted with a tilting drive or a portion of the table adjoining the cylinder and provided with front gages is longitudinally displaceably guided, taken along by a driver of the cylinder during its backward swing and following after 10 the change in the direction of rotation of the cylinder owing to the action of a spring.
6. A printing machine according to claim 2, in which when the sheets are directly taken off from the feed table by the cylinder grippers, the feed table being formed in known manner as a swinging table and fitted with a tilting means for a portion of the table adjoining the cylinder and provided with front gages is longitudinally displaceably guided and is forwardly moved by a 20 driver on the cylinder during its backward swing and rearwardly moved after the change in the direction of rotation of the cylinder owing to the action of a spring and in which the longitudinally displaceably guided feed table or portion of 25 the table is provided with means, as suction nozzles, for securing the sheets in adjusted position.
7. In a printing machine, a frame, a cylinder mounted for oscillatory movement in said frame, means to oscillate the cylinder, a feed table 30 mounted for swinging movement of its forward edge toward and from said cylinder, stop gages positioned for contact by the forward edge of a sheet when carried on said table upon the forward edge of the table being swung away from the cylinder, means supporting said table for longitudinal reciprocation toward and from the cylinder, grippers carried by said cylinder to grip 35 the forward edge of the paper upon the table

being at the forward end of its reciprocatory movement, and means to reciprocate the table in timed relation to the oscillations of the cylinder.

8. In a printing machine, a frame, a cylinder mounted for oscillatory movement in said frame, 5 means to oscillate the cylinder, a feed table mounted for swinging movement of its forward edge toward and from said cylinder, stop gages positioned for contact by the forward edge of a sheet when carried on said table upon the forward edge of the table being swung away from the cylinder, means supporting said table for longitudinal reciprocation toward and from the cylinder and including a supplemental frame pivoted at its forward end to the first frame, grippers carried by said cylinder to grip the forward edge of the paper upon the table being at the forward 10 end of its reciprocatory movement, and means to reciprocate the table in timed relation to the oscillations of the cylinder. 20

9. In a printing machine, a frame, a cylinder mounted for oscillatory movement in said frame, means to oscillate the cylinder, a feed table mounted for swinging movement of its forward edge toward and from said cylinder, stop gages 25 positioned for contact by the forward edge of a sheet when carried on said table upon the forward edge of the table being swung away from the cylinder, means supporting said table for longitudinal reciprocation toward and from the 30 cylinder and including pivots supporting said table adjacent the rear edge thereof, grippers carried by said cylinder to grip the forward edge of the paper upon the table being at the forward 35 end of its reciprocatory movement, and means to reciprocate the table in timed relation to the oscillations of the cylinder. 25

GEORG SPIESS.
